UNITED STATES PATENT OFFICE.

BERNARD T. STEBER, OF UTICA, NEW YORK.

MACHINE FOR MAKING PAPER-BOXES.

SPECIFICATION forming part of Letters Patent No. 279,285, dated June 12, 1883.

Application filed October 30, 1882 (No model.)

To all whom it may concern:

Be it known that I, BERNARD T. STEBER, a citizen of the United States, residing at Utica, in the county of Oneida and State of New York, 5 have invented a new and useful Improvement in Machines for Making Boxes of Paper or other Flexible Material for Matches or for other Uses, of which the following is a specification.

10 Heretofore in the manufacture of boxes, of paper or other flexible material, by machinery, consisting of a vertically-reciprocating plunger, rigid die-walls, and folding devices in the same vertical passage-way as that in which the 15 plunger is moved, difficulty has been experienced from the fact that no provision is made for the yielding of the walls to accommodate paper of varying thickness, and a like difficulty has been experienced, with paper-box 20 machines wherein fingers and springs have been employed, in keeping the complicated system of controlling fingers and springs in working order, as the variation in the thickness of paper or other material often prevents them from properly performing their 25 office; and the object of my invention is to produce a machine whereby the paper or other flexible material used can be automatically folded into the shape of a box in the simplest 30 possible manner, such machine being simple and positive in its operation, and thus rendering the use of a system of complicated fingers and springs unnecessary, and obviating the difficulties experienced from the use of the 35 same.

In the accompanying drawings, Figure 1 is a top view of my improved machine, parts not exposed being shown by dotted lines, and the cut paper being also shown in position for 40 folding by dotted lines. Fig. 2 is a vertical longitudinal section of the machine, the plunger and piece of paper being shown in dotted lines in the position they occupy when the piece of paper which is to be folded into a 45 box is ready to have the first fold imparted to it, and the plunger also being shown by full lines in the position it occupies after it has been so operated as to form the first fold in the piece of paper. Fig. 3 is a vertical 50 transverse detail section of Fig. 1. Fig. 4 is a detail broken longitudinal section, showing

the plunger with the piece of paper folded so as bear upon its bottom and two sides and forward end, and ready to be folded again upon its sides, and then upon the end and top of the 55 plunger. Fig. 5 is a detail longitudinal section, showing the piece of paper folded down upon the top of the plunger, and the plunger just on the eve of passing between the first pair of folders. Fig. 6 is a detail horizontal section 60 of the folding devices which make the second fold of the paper upon the sides of the plunger, and the devices which fold it finally upon the sides of the same while it is held down against the top of the same. Fig. 7 is a vertical trans- 65 verse detail section, showing the parts in the act of finishing the box, or the plunger with paper box upon it passing between the final pair of folders. Fig. 8 shows in perspective the paper as cut for forming a box; Fig. 9, the 70 paper as first folded; Fig. 10, as with its second fold; Fig. 11, as with its third fold; and Fig. 12, as with its final fold, or in form of a finished box; and Fig. 13 is a perspective view of the finished box shown in Fig. 12 turned 75 over so as to show the short intermediate lap of the box.

In the views, A is a foundation-piece, upon which guideways *a* and a rock-shaft, *b*, are mounted. Upon the rock-shaft a vertically-vibrating-lever, *B*, is applied rigidly, and between the guideways a slide, *C*, with a plunger-rod, *C'*, and plunger *C''*, attached to it, is applied, so as to move horizontally in a longitudinal direction. The plunger-rod is fitted loosely 80 between upright guide-pieces *c*, and is connected loosely by a pendent eye-bracket, *d*, to the lever *B*, while its rear end is attached to a rock-shaft, *e*, journaled in the slide. The plunger is of oblong form, with rectangular or 85 other properly-shaped sides, accordingly as the style of boxes to be made may require. The plunger can be swung up to the position shown by dotted lines in Fig. 2 by moving the lever *B*, with its rock-shaft *b*, and the plunger-rod, with its rock-shaft *e*, and it can be moved 90 horizontally when down upon the platform *A*, as shown in full black lines in Fig. 2, by moving the slide *C* between the guideways either 95 forward or backward.

In the bottom of the bed-plate of the foundation a T-shaped slot, *f*, is provided, and be-

low the plunger a T-shaped spring-holding bridge-piece, *g*, is applied, it being fastened in rear of the plunger to the eye-bracket, as shown. This T-shaped bridge-piece passes 5 down through the slot *f* when the plunger is resting on the bed-plate of the foundation, and its forward end occupies a position, during the act of feeding, on a plane a little higher than that on which the paper from which the boxes 10 are to be made is fed into the machine, and its office is to hold up the paper until it has passed over and beyond the vertical sides of both of the side walls of the die which forms the first fold in the paper from which the box is formed. 15 This is a very important part of my invention, as it avoids premature bending down of the paper into the passage-way of the plunger by the same incidentally striking against one of the side walls of said passage-way. On the 20 sides of the plunger yielding vertical walls *h h* are provided, and from the upper edges of these walls horizontal tables *i* extend. These side walls and tables are fastened to bent spring-plates *j*, which are attached to the bed- 25 plate of the foundation, so as to permit the plates and tables to move horizontally a sufficient extent to accommodate the variant thickness of paper or other material which may come between the side walls and the plunger in the 30 manufacture of the boxes. Forward of and attached to or forming parts of the springs are oblique vertical portions *k*, which touch with their forward ends the outer surfaces of the walls *h h*. These spring portions, together 35 with the side walls, aid in controlling the paper during the impartation thereto of the first fold, the portions 1 of the paper resting against the side walls when the plunger has descended from the position shown in dotted 40 lines in Fig. 2 to the position shown in full black lines in same figure. The tables *i*, together with the bridge-piece *g*, support the portions 1 and 3 of the paper until it is operated upon by the downward stroke of the 45 plunger.

Beyond the tables *i*, and with a space, *l*, between it and the tables, is a broader table, *i'*, which serves for supporting the portions 2, 4, 5, 6, and 7 of the paper when it is first fed into 50 the machine and until the plunger has folded it into the form shown in Fig. 9. The fold at 4 is effected by the paper being forced down through the space *l* and kept against the end of the plunger by the edge of the table *i'*. Beneath this table a chamber, *i''*, is provided, and at one end of this chamber a pair of divergent curved spring-folders, *m*, are applied, as shown, and at the other end another pair of beveled 55 convergent oblique folders, *n*, are provided, the latter being applied to a plate fastened to the under side of the table *i'*. The folders *m* serve for folding the portions 2 of the piece of paper against the folded portions 1 thereof while the plunger is passing under the table *i'*, and at 60 the same time the under surface of the table *i'* and the plate fold the portion 5 upon the top

of the plunger, and the forward movement of the plunger being continued, the inclined edges *n'* of the folders *n* turn the portions 6 and 7 downward against the sides of the plunger upon 70 the folded portions 2 and 1, while the oblique vertical sides of these folders firmly fold the portions 6 and 7 in the position shown in Fig. 12. The box being now completed, the plunger is moved beyond the rear end of the table 75 far enough to admit of the removal of the box.

To my machine can be attached the feed cutting and gluing contrivances which are now in common use, and in operating with my machine the paper will be supplied from rolls the 80 same as used in ordinary telegraph-machines, and while being fed sidewise of the machine, as signified by dotted lines *W W* in Fig. 1, it will be prepared with glue, then cut, as signified in Fig. 8, and when it is fed under the 85 plunger it will be cut off to the proper length, and as soon as this occurs the plunger will be made to descend and slide, as hereinbefore set forth.

The lever which vibrates the plunger may 90 be limited in its upward movement by a gage-stop, *o*, which is applied to the rock-shaft *b*, and strikes against the bearing *o'*, as shown, or by any other suitable stopping device; and this lever may be operated either by hand or 95 power mechanism connected with it in any suitable manner.

The plunger-slide may be limited in its backward movement by a gage-stop, *p*, and it may be moved back and forth either by hand or 100 power mechanism, as may be deemed best. Either a lever connected to the plunger-slide in any suitable manner or a toothed rack and pinion may be adopted as the means for reciprocating the plunger in a rectilinear direction. 105 I contemplate employing mechanism or means in such a manner that the vibrating movement of the plunger and the reciprocating movement of the same will be timed so that when the plunger has descended to make the first 110 fold in the paper the longitudinal movement will immediately thereafter take place.

I do not confine my invention to a plunger which slides, as the vibrating plunger may be employed in connection with a sliding chamber, 115 in which the folders *m n* are applied and moved toward and past the plunger.

What I claim as my invention, and desire to secure by Letters Patent, is—

1. The vibrating lever, in combination with the vibrating plunger, the foundation, yielding side walls, and tables, whereby the first fold is made in the paper or other material, substantially as described.

2. The vibrating lever, which raises and lowers the vibrating and sliding plunger, in combination with the plunger, substantially as and for the purpose described.

3. The bridge-piece between the side walls, in combination with the plunger and yielding side walls, substantially as and for the purpose described.

4. The combination of the slotted foundation, the bridge-piece, and the plunger, substantially as and for the purpose described.
5. The bridge-piece connected with the vibrating lever and loosely fitted upon the plunger-rod, as at *d*, in combination with a plunger which is arranged to vibrate and reciprocate, substantially as and for the purpose described.
6. The combination of means consisting of the yielding side walls, *h h*, tables *i i'*, and foundation A, which aid to form the bottom or end 4 and one side, 3, and the two inside folds or laps, 1 1, of the two opposite sides, 6 and 7, of the box, and the vibrating lever and vibrating plunger, substantially as and for the purpose described.
7. In combination with the vibrating and
- sliding plunger and devices which aid to effect the first folds of the paper, the diverging folders which form the two side folds or laps, 2 2, 20 of the bottom 4 of the box, substantially as and for the purpose described.
8. In combination with the vibrating and sliding plunger and the devices employed in effecting the first and second folds of the paper, 25 the converging finishing-folders with inclined lower edges, whereby the opposite sides, 5, of the box and two outside folds or laps, 6 and 7, are formed and the box finished, substantially as described.
